FLOW MONITOR

Stephens N. Sato, San Diego, Calif., assignor to Ivac Corporation, San Diego, Calif., a corporation of California

Filed Mar. 17, 1969, Ser. No. 16,269

Term of patent 14 years

Int. Cl. D10—11

U.S. Cl. D52—6

Fig. 2

Fig.3

Fig.4

Fig.5

FIG. 1 is a front perspective view of a flow monitor embodying my new design;

FIG. 2 is a top plan view of the flow monitor shown in FIG. 1; and

FIG. 3 is a rear elevational view of the flow monitor shown in FIG. 1;

FIG. 4 is a bottom plan view of the flow monitor shown in FIG. 1; and

FIG. 5 is a right side elevational view of the flow monitor shown in FIG. 1.

I claim:

The ornamental design for a flow monitor, as shown.
